CLAIM

The ornamental design for a housing for laser machining center, substantially as shown and described.

DESCRIPTION

FIG. 1 is a perspective view of housing for laser machining center in accordance with the design.

FIG. 2 is a front view of housing for laser machining center in accordance with the design.

FIG. 3 is a rear view of housing for laser machining center in accordance with the design.

FIG. 4 is a left side view of housing for laser machining center in accordance with the design.

FIG. 5 is a right side view of housing for laser machining center in accordance with the design; and,

FIG. 6 is a top view of housing for laser machining center in accordance with the design.

Any broken line showing environment structure is for illustrative purposes and forms no part of the claimed design.
